THE JEFFREY MANUFACTURING COMPANY, A CORPORATION OF CHIC.

LOCOMOTIVE WITH CABLE-REELING MECHANISM.

1,137,236.

Specification of Letters Patent.

Patented Apr. 27, 1915.

Application filed September 12, 1907, Serial No. 392,577. Renewed February 23, 1915. Serial No. 10,130.

To all whom it may concern:

Be it known that I, FRANK L. SESSIONS, a citizen of the United States, residing at Columbus, in the county of Franklin and State 5 of Ohio, have invented certain new and useful Improvements in Locomotives with Cable-Reeling Mechanism, of which the following is a specification, reference being had therein to the accompanying drawings.

10 This invention relates to haulage locomotives of the sort used in mines for gathering or collecting loaded cars. In coal mines, operated on the room and pillar plan, it is the practice to mine the coal at each of numerous points. After the masses are 15 loosened the cars are distributed, one being taken to each of the places of mining. After they are loaded they are brought individually from the rooms to the place where 20 they are coupled into trains or "trips."

Electric locomotives are now largely used for handling the cars and "gathering" them into trains or "trips," and it is to locomotives adapted for this purpose that my 25 invention especially relates. The rooms and branch mine passageways leading to the rooms of a mine are, as a usual rule, not equipped with a trolley wire or other extended stationary conductor for supplying 30 current to the locomotives. The tracks in these branch passageways and rooms where the coal is cut and loaded are temporary in character, and it is uneconomical to provide trolley wire equipment over these temporary 35 tracks. The main passages of the mines are equipped with trolley wires. When the locomotives leave these main entries to enter the rooms, current must be supplied them by some means other than running contact 40 of the trolley wheel with the trolley wire. One of the means quite generally employed for this purpose, is a flexible conductor cable which is wound upon a reel carried by the locomotive and is attachable at its free 45 end to a trolley wire at the point where the locomotive leaves the trolley-equipped entry.

In many cases it is found undesirable to advance the locomotives themselves into the far parts of the rooms where the cars are 50 located. In order that the cars may, under these circumstances, be hauled out, it has been heretofore proposed to provide the locomotive with a reel and a haulage cable adapted to be wound upon the reel. The 55 free end of the cable can be carried into the

room and attached to the car and then by rotating the reel the car can be hauled out.

A locomotive embodying my invention has both of the mechanisms which have been referred to. It has one reel upon which is wound an electric conductor cable for supplying current to the locomotive motor and another reel provided with a haulage cable adapted to be attached to a car.

One of the objects of my invention is to 65 provide a single motor connected and arranged to drive either the locomotive itself or the electric cable or the haulage cable reel or any two or all three of these simultaneously.

Another object is to provide improved power transmitting mechanism for driving the reels, and improved devices for controlling this power transmitting mechanism.

A further object is to provide an improved arrangement of the reels and the driving mechanism therefor and an improved means for supporting the reels and the driving mechanism.

Still further objects will be apparent from 80 the following specification and claims.

I do not claim as a part of my present invention the winding mechanism and the driving and controlling devices therefor so far as these are capable of use independently 85 of a locomotive, as they are covered by a separate application for winding mechanism, Serial No. 587,975, filed October 19, 1910, as a division of this application.

Of the accompanying drawings, Figure 1 90 is a top plan view of a locomotive embodying my improvements. Fig. 2 is a side view, part of the locomotive being shown in side elevation and part in central vertical longitudinal section. Fig. 3 is a cross-sectional view of one of the car axles and the gearing immediately adjacent thereto. Fig. 4 is an end elevation of the reeling devices and the frame supporting them, the side parts of the locomotive being shown in vertical section. Fig. 5 is a fragmentary detail view, showing the locking mechanism for one of the clutches.

The locomotive shown is formed with cast iron side frame elements 1 and 2. These are 105 preferably cast integral from end to end. At their ends they are connected to cross frame pieces 3, 4, each of these also being integral from side to side. Each of the side pieces is formed with two rectangular 110

openings and in each opening there is fitted the journal box or bearing for receiving the end of an axle. The axles are indicated respectively by 6 and 7. In the space between the axles there is mounted an electric motor 8 to which current is usually supplied by trolley mechanism indicated by 9, this being of any suitable character. Just inside of the end cross piece 3 of the frame 10 there is a chamber or space within which are located the parts by which the motorman is enabled to control the locomotive and manipulate various parts carried thereby.

10 indicates an electric controller which is preferably in circuit between the trolley mechanism and the motor. A wheel brake system is shown, but as this is not within the scope of the invention to which the present application relates it is unnecessary to describe it in detail. The brake mechanism is operated by a hand wheel and screw at 12 which are mounted in a cross bearing bar 12. The electric motor is connected to one of the axles by gearing and this axle is connected by a sprocket 13 and a chain with a sprocket wheel 14 on the other axle, so that power is transmitted to both. The armature shaft of the motor is by means of the coupling at 15 coupled to a shaft 46 which carries the worm 45. This worm engages with a worm wheel 15 on the axle 6. The wheel has hubs, one on each side, 16 and 17, which are provided with anti-friction linings 18 and 19. The hub 16 abuts against sprocket 13 on one side of the wheel and the hub 17 abuts against a collar 20 on the axle. On the hub 17 of the worm wheel 15 there are clutch teeth 21 with which engage the teeth on an opposing clutch element 22. The latter is connected to the axle 6 by a feather or spline and can be moved into or out of engagement with the clutch element at 21 by means of the shifting devices comprising fork 23, a rock shaft 24 and a hand lever 25 near the motorman, the shaft 24 being mounted in the bracket bearings at 26, 27. The worm and worm gear are inclosed in a case having the upper part 30 and the lower part 35. The upper half 30 is formed with the half hubs 31 and 32 and the lower part with the half hubs 36 and 37. The casing, when these parts are secured together, has a bearing on the hubs 16 and 17 of the worm wheel, there being removable lining bushings 33 and 34 interposed between the casing and the wheel hubs.

The casing is connected to the sides of the motor by arms 38, 39, extending backward and bolted to the flanges 40, 41, formed in the motor metal. These arms and the casing serve to support the front end of the motor.

The other end of the motor, where the commutator is situated is supported by a

stirrup 42 bolted to the sides of the motor frame and resting in the clevis 43, the latter being bolted to a cross bar 44 which rests in suitable recesses in the side frames at 1 and 2.

The worm 45 above referred to is mounted on the shaft 46 and has thrust collars 47 and 48, one on each side, provided with ball bearings. The worm shaft 46 is supported in bearings 49 and 50 on the upper part of the gear case 30. Part of the gear case is a cap 52 which can be fastened in place by bolts.

The pitch of the thread of the worm 45 and of the teeth on the worm wheel 15 is such that the gearing is "overhauling," and that the worm wheel will drive the worm when the locomotive is coasting or drifting, as for example, when the current is cut out of the motor and the car is still advancing and its axle rotating.

The lower part of the gear case is filled with oil and the wheel 15 carries it up, constantly and efficiently lubricates the worm. Some of the oil that is lifted by the wheel will pass through the apertures 53 into the chamber 54, whence it will work itself outward along the face of the axle and will lubricate the journals at 18 and 19. The casing is provided with grease cups for lubricating the outer journals at 33 and 34.

The reeling mechanism is carried by a frame indicated at 57, 58 and 59. This frame is supported by bars 55, 56, which are secured to the side parts 1 and 2 of the car body frame extending across from one to the other. The upper part of the frame 57 has flanges at the bottom, to which are bolted the lower parts of the frame, the castings 58 and 59. Mounted in this frame is a vertical shaft 60 carrying a worm wheel 61, and these are driven by the worm 62 on the shaft 63. This shaft receives power from the sprocket wheel 66 on the end of the above mentioned worm shaft 46, through a chain 65 connected to a sprocket wheel 64 on the worm shaft 63. The casting 58 above referred to and a supplemental casting 67 are so formed and secured together as to inclose the worm 62 and the worm wheel 61, and moreover they are formed with bearings for the shaft 63. The said castings 58 and 67 have vertically extending bosses or hubs 68 and 69 which furnish bearings for the vertical shaft 60.

The frame casting 57 is extended upward to a horizontal plane sufficiently high and is formed with a real support 57^a shaped to provide part of a ball race 70. In this are placed a suitable number of steel balls 71. And on these a holder in the form of a cast iron ring 72 is arranged to rest, this having a circular groove to form the upper element of the ball race. The upper surface of this holder or ring 72 is flat as shown at 73, but

its outer edge is provided with square teeth as at 74, to provide a ratchet.

76 is a pawl pivoted to the stud 75 which is secured to the upper part of the frame 5 piece or casting 57, this pawl being adapted to engage the ratchet teeth at 74. 77 is a counterweight also pivoted to the stud 75 and connected to the pawl 76 by the bolts 78. The pawl has two active ends, one projecting to the right from the pivot 75 and the other to the left. It has also two points of attachment for the bolt 78 to the weight 77. By transferring the weight and bolt from one side to the other of the center the direction of action of the pawl can be reversed.

79 indicates the cable reel, preferably formed in the way shown and resting upon the flat surface 73 of the holder 72 and adapted to revolve with the ring on the balls 20 at 71 without frictional resistance. When, however, the ring or holder 72 is prevented from revolving by the pawl and ratchet, the reel can be revolved only by sliding or slipping on the face 73, which forms a brake to prevent the cable from being unwound more freely than is desired at times.

At the axis of the reel there is a shaft 83 in line with but separated from the aforesaid lower shaft 60. The upper shaft 83 is mounted in and projects upwardly from the top of the frame part or casting 57. Between this shaft and the reel there is interposed a friction clutch. One member of this is a plate or flange 80 projecting inwardly from the periphery part of the reel. The other member is composed of two plates or flanges 81 and 82 keyed to the shaft 83, these overlapping a central annular part of the flange or plate 80, one lying above and the other lying below it. Frictional engagement under pressure is produced by means of a spring 83^a and the adjustable nuts 83^b both above the clutch plate 82, the spring acting to clamp the plates 81 and 82 against the horizontal surfaces of the flange or plate 80. The shaft 83 is shouldered just below the plate 81 to prevent the spring 83^a from causing any relative movement of plate 81 and the shaft.

84 indicates the bearing for the shaft 83, it being central with the ball-race 70 and serving to retain the reel and the clutches in proper position. There is sufficient clearance to allow the entire shaft 83 and the 55 clutch plates, to rest under their weight on the ring 72 and the balls 71. Shaft 83 projects below bearing 84 and upon it there is slidably mounted a right-hand spiral jaw clutch 85 normally tending to drop downward a certain distance under its own weight.

86 is a shifting fork which engages with and carries the weight of this clutch member. The fork is secured to the rock shaft 87 which is mounted in bracket bearing

88-89 formed on or secured to the stationary frame or casting 57.

90 is a rocker arm or crank secured to the shaft 87, and 91 is a shifting rod connected to this rocker arm and extending to the 70 motorman's end of the locomotive. At its rear end this rod 91 rests on the cross bar 12^a and is held against it by the tension spring 91^a. It is enlarged to form a latch 91^b so shaped that when the clutch 85 is in 75 contact with the opposing clutch-element 93, this latch will rest on top of the cross bar 12^a, as shown in Fig. 5 but as the rod is drawn backward the bevel face of the latch will be forced downward and backward by 80 the spring 91^a and the clutch member 85 will be lifted to the frame casting 57.

The shaft 60, above described, carries at its upper end the right-hand spiral jaw clutch member 92. Between this and the aforesaid clutch member 85 there is interposed a clutch ring 93 having two sets of clutch teeth, a set of right-hand teeth on its upper face and a set of left-hand teeth on its lower face. It may be clamped to either of the parts 85 and 92 by clamping ring 94 having inwardly projecting flanges which correspond to suitable grooves in the three clutch members. By means of this clamping ring the clutch can be readily converted from 95 right-hand to left-hand or from left to right as may be desired. The flange 80, of the reel 79, also serves as a support for the ring of insulation at 95 to which is secured the collector ring 96. The electric cable 96^b (for the 100 winding of which the reel is employed) has the inner end of its conductor electrically connected to this collector ring 96, the end part of the cable being passed through the aperture in the reel periphery at 96^a and a 105 binding lug 97 being provided for firmly fastening the end of the metallic conductor. From the collector ring 96, the current is taken to a stationary circuit terminal at 100 by means of the contact finger 99, carried by 110 the insulating block 98 and supported upon the stationary frame casting 57 in such way as to press against the collector ring.

The cable can be taken to and from the reel as it is being wound or unwound from 115 points along the track either in front of or behind the locomotive. At each end of the locomotive there are mounted upon the side frames 1 and 2 suitable guide rollers 1^a and 2^a to properly direct the cable as it is being 120 taken up or paid out. The devices above described are for the purpose of conducting current to the electric apparatus on the car when the trolley mechanism is out of operation. For instance, when isolated cars are 125 to be taken out of the mine rooms after they have been loaded and gathered on the tracks in the entries for making up trains, and when these cars are at a distance from the main current-supplying wires the cable is 130

availed of for actuating the motors on the locomotives. But, under many circumstances, it is desirable to be able to draw the loaded isolated cars from the rooms while the locomotives are standing still in the entry and the following apparatus in the present mechanism enables this to be done.

The shaft 60 hereinbefore referred to has a friction cone 101 secured thereto. Below this there is a second reel 102, mounted loosely on the shaft 60 and provided with a haulage cable 102^b of steel or other suitable material adapted to be wound thereon and unwound when needed. This reel is formed 15 with a concave frictional conical part 102^a. Normally the reel 102 with its cone 102^a is a short distance below and out of contact with the rotating cone 101. But, they can be lifted, when desired, so as to contact 20 therewith by means of a cam ring 103 meshing with the cam surfaces 104, the latter being cast into the hub 105, formed with the bottom part 59 of the stationary frame. The hub 105, at its center, also provides a step- 25 bearing for the shaft 60. There is a ball bearing 106 between the cam-lifting ring 103 and the lower face of the hub of the reel 102 to reduce friction to a minimum.

When it is desired to lift the ring 103, and 30 the reel, the ring is rotated by an arm 107 which extends laterally therefrom, this arm being hinged to a draft rod 108, which in turn is connected to the lever 109, at the motorman's end of the locomotive. A spring 35 110 is so combined with the lever 109 and rod 108 as to allow the parts to yield somewhat when necessary; and by means of the thumb-latch 111 and the ratchet segment 112 the lever 109 and its connected parts can be 40 fastened in any desired position of adjustment.

113 indicates a series of ratchet teeth or ratchet wheel secured to or formed with the reel 102. With these teeth a pawl 114 engages, this pawl being supported by lugs 45 on the frame casting 59 and when in engagement the rotation of the reel in one direction is prevented. Pawl 114 can be lifted out of engagement by the rod 115, which is done 50 when the operator desires that the reel shall revolve in the direction last referred to.

The haulage cable (not electric) passes from the reel 102 through an opening in the end frame 4 between two guide sheaves 55 or pulleys 116 and 117, and at its free end this cable is provided with a suitable coupling device for attaching it to the mine cars.

The operation of this haulage reel is as 60 follows: The locomotive, having arrived at the room mouth, the clutch lever 25 is pressed downward, thereby rotating the shaft 24 and shifting fork 23, disengaging the clutch 22. The rod 115 being pulled 65 toward the rear, the pawl 114 will be lifted

out of engagement with the ratchet 113, allowing the reel 102 to revolve freely as the trip rider pulls the cable out. After the cable is hitched to the pit car, the pawl 114 is dropped, the lever 109 is depressed until 70 the pressure between the reel 102 and the cone 101 is sufficient to drive the reel 102. By means of the controller 10, the motor 8 is started in the proper direction to cause the cable to be wound up, and the car is drawn 75 out of the room, after which the lever 109 is released, and the clutch 22 reengaged. The unwinding of the cable will now be prevented by the pawl 114, and the car can be 80 taken to its destination without changing 85 the hitch.

The operation of the electric cable reel is as follows: The cable having been wound on the reel in the proper direction, it is desired to take the locomotive into a room where 85 there is no trolley wire. The free end of the cable is connected with the trolley wire by appropriate attachments, and the trolley is locked in such a position as to be out of the way. The motor now receives current through the cable and the collector mechanism on the reel, and may be run into the room, the cable unwinding as the locomotive proceeds. As the pawl 76, engaging 90 the ratchet 74, prevents the revolution of 95 the brake ring 72, the reel 79 will slide on the face 73 of the brake ring 72, the retarding effect of which will prevent too rapid unwinding of the cable, and tend to hold it off the ground. Before starting to return, the 100 operator pushes the rod 91 forward until the latch 91^b rests on top of the cross bar 12^a. This will cause the clutch 85 to engage with the clutch 93, and, when the locomotive starts, the friction disks 81 and 82 will cause 105 the reel to revolve in the winding direction. As the pawl 76 does not prevent the ring 72 from revolving in this direction, the whole device revolves on the ball bearings 71 without unnecessary friction. The proportions 110 of the reel and its driving members are such that the tendency is for the reel to revolve faster than the cable will wind. This is compensated for by the slipping of the friction clutch members 81 and 82 against the 115 flange 80, the pressure of the spring 83 being so adjusted as to keep a desirable tension 120 on the cable. When the locomotive reaches the entry, and the cable is disconnected from the trolley wire, the clutch 85 should be thrown out to prevent unnecessary wear on the friction members 80, 81 and 82; but, if the direction of the locomotive is reversed, the clutch member 85 will climb on the face 125 of the clutch member 93, thus rocking the arm 90, which will push the rod 91 forward until the latch 91^b slips over the edge of the cross bar 12^a, and the spring 91^a will force the rod clear back and insure the clutch 85 clearing the teeth on 93.

If for any reason it is desired to use the locomotive in a part of the mine where it will be necessary to enter the rooms rear end first, the clamping ring 94 may be shifted to 5 clamp the ring 93 to the clutch 85, making a left hand clutch instead of a right hand; the counterweight 77 shifted to the other side of the pawl 76; and the cable entirely unwound and rewound in the opposite direction; after 10 which the operation is as before.

What I claim is:

1. In an electric locomotive, the combination with a main frame, and axles and track wheels upon which the frame is mounted, of 15 a reel rotatably mounted upon the frame and adapted to have a cable wound upon it, a motor on the frame, power transmitting mechanism between the motor and the reel, a gear rotatable concentrically on one of the 20 axles, power transmitting mechanism between the motor and the said gear, and a manually controllable clutch mounted concentrically on the axle and adapted to connect the gear and the axle.
2. In an electric locomotive, the combination with a main frame, and axles and track wheels upon which the frame is mounted, of 25 a reel rotatably mounted on the frame and adapted to have wound upon it an electric conductor cable, a second rotatable reel adapted to have wound upon it a haulage cable, a motor, power transmitting mechanism between the motor and each of the 30 reels, a gear mounted concentrically with 35 one of the axles and rotatable with respect thereto, power transmitting mechanism between the motor and the said gear, and a manually controllable clutch interposed between the gear and the axle.
3. In an electric locomotive, the combination of track wheels and axles for supporting the locomotive, a rotatable reel adapted 40 to have an electric conductor cable wound upon it in either direction, an electric motor, power connections between the motor and the 45 reel, and power connections comprising a clutch between the motor and one of the axles.
4. In an electric locomotive, the combination of axles and track wheels for supporting the locomotive, a rotatable reel adapted 50 to have an electric conductor cable wound upon it, an electric motor, power transmitting mechanism comprising a friction clutch between the motor and the reel, and power transmitting mechanism comprising a clutch 55 between the motor and one of the axles.
5. In an electric locomotive, the combination of a frame, axles and track wheels for supporting the frame, a rotatable reel adapted 60 to have an electric conductor cable wound upon it, an electric motor, power transmitting mechanism comprising a manually controllable clutch between the motor and the 65 reel, and power transmitting mechanism

comprising a manually controllable clutch between the motor and one of the axles.

6. In an electric locomotive, the combination of a frame, axles and track wheels for supporting the frame, a rotatable reel adapted to have an electric conductor cable wound upon it, an electric motor, power transmitting mechanism comprising a manually controllable clutch and a continuously acting friction clutch between the motor and the 70 reel, and power mechanism comprising a clutch between the motor and one of the axles.

7. In a locomotive, the combination of a car, a reel adapted for winding and unwinding an electric conductor cable, an electric motor mounted on the car, gearing between the motor and one of the car axles, additional gearing between one of the elements of said gearing and the reel adapted to 75 transmit power from the said element to the reel, and a clutch for disconnecting the axle from the first said gearing.

8. The combination in an electric locomotive, of track wheels and axles upon which the locomotive is supported, a rotatable reel, adapted for winding and unwinding an electric conductor cable, an electric motor, a gear operatively mounted on one of the axles, a gear meshing with the gear on the axle, and power transmitting connections independent of the said axle between the said meshing gear and the motor and between said meshing gear and the reel.

9. In an electric locomotive, the combination of track wheels and axles upon which the locomotive is supported, a rotatable reel adapted for winding and unwinding an electric conductor cable, a rotatable shaft, a power transmitting mechanism connecting the shaft at a point intermediate its ends with one of the axles, an electric motor operatively connected with the shaft at one end, and power transmitting mechanism extending between the other end of the shaft 105 and the reel.

10. In a locomotive, the combination of a car, a reel, adapted for winding and unwinding an electric conductor cable, an electric motor, gearing between the motor and one 110 of the car axles, and other gearing independent of the said axle for connecting one of the elements of the first said gearing with the reel whereby when the motor is deenergized the reel can be driven by power from the 115 axle in the same direction as it is driven by the motor when the latter is energized.

11. In a locomotive, the combination of a car, a reel adapted for winding and unwinding an electric conductor cable, a worm gear 120 on one of the car axles, an electric motor, a shaft driven by the motor, a worm on said shaft meshing with the worm gear on the axle, and power transmitting mechanism separate from the worm and worm wheel 125 130

- for connecting the shaft with the reel, the arrangement being such that the motor can drive the axle through the said worm and worm wheel and simultaneously drive the reel through the said power transmitting mechanism.
12. In a locomotive, the combination of a car, a reel adapted for winding and unwinding an electric conductor cable, an electric motor, a power connection between the motor and the reel comprising worm and wheel gearing and a shaft, and power transmitting mechanism connecting the shaft with one of the car axles, the said power transmitting mechanism being independent of the said worm and wheel gearing and meshing with the said worm, the arrangement being such that the motor can drive the reel through one worm and wheel gearing and simultaneously drive the axle through the other worm and wheel gearing.
13. In a locomotive, the combination of a car, a motor thereon, a reel, adapted for winding and unwinding an electric conductor cable, a power transmitting mechanism connecting the motor with one of the car axles comprising an overhauling worm gearing, additional power transmitting mechanism independent of the said axle for connecting the worm shaft of the said worm gearing with the reel for the transmission of power thereto, the arrangement being such that the motor can drive the car axle through the said worm gearing and simultaneously drive the reel through the said additional power transmitting mechanism.
14. In a locomotive, the combination of a car, a motor thereon, a reel, adapted for winding and unwinding an electric conductor cable, power transmitting mechanism between the motor and one of the car axles comprising an overhauling worm gearing of which the worm is operatively nearer the motor, and further comprising a shaft upon which the said worm is mounted, additional power transmitting mechanism independent of the said axle for connecting the shaft with the reel for the transmission of power thereto, and a clutch arranged to disengage the reel from the said shaft, the arrangement being such that the motor can drive the axle through the said worm gearing and can simultaneously drive the reel through the said additional power transmitting mechanism.
15. In a locomotive, the combination of a car, a motor thereon, a reel adapted for winding and unwinding an electric conductor cable, a worm gear wheel arranged to drive one of the axles, a shaft, a worm upon the shaft meshing with the said worm gear wheel, power transmitting devices between the worm shaft and the motor, and additional power transmitting devices independent of the said axle between the worm shaft and the reel, the arrangement being such that the motor can drive the car axle through the said worm and worm wheel and simultaneously drive the reel through the said additional power transmitting devices. 70
16. In a locomotive, the combination of a car, a motor thereon, a cable reel adapted for winding and unwinding an electric conductor cable, gearing between the motor and one of the car axles comprising an overhauling 75 worm gear, and power transmitting mechanism connecting the car axle through the worm gear with the reel.
17. In an electric locomotive, the combination of a main frame, axles and track 80 wheels upon which the frame is supported, a motor for driving the locomotive, a rotatable shaft on the locomotive, a reel adapted for winding and unwinding an electric conductor cable, a second rotatable reel 85 adapted for winding and unwinding a haulage cable, and power transmitting connections between the rotating shaft and both of the reels.
18. In an electric locomotive, the combination of a main frame, axles and track 90 wheels upon which the frame is mounted, a motor for driving the locomotive, a rotatable shaft on the locomotive, a reel rotatably mounted on the locomotive and adapted to 95 wind and unwind an electric conductor cable, a second reel adapted to wind and unwind a haulage cable, a power transmitting connection between the rotatable shaft and the first reel, and a power transmitting connection 100 comprising a manually controllable clutch between the shaft and the second reel.
19. In an electric locomotive, the combination of a main frame, axles and track 105 wheels upon which the frame is mounted, a motor for driving the locomotive, a rotatable shaft on the locomotive, a reel rotatably mounted on the locomotive and adapted to wind and unwind an electric conductor cable, a second reel adapted to wind and 110 unwind a haulage cable, a power transmitting connection between the shaft and the first reel, and a power transmitting connection 115 comprising a manually controllable friction clutch interposed between the rotatable shaft and the second reel.
20. In an electric locomotive, the combination of a main frame, axles and track 120 wheels upon which the frame is mounted, a motor for driving the locomotive, a rotatable shaft on the locomotive, a reel rotatably mounted on the locomotive and adapted to wind and unwind an electric conductor cable, a second reel adapted to wind and 125 unwind a haulage cable, a yieldable friction controlled power transmitting connection between the rotatable shaft, and the first reel and a power transmitting connection between the shaft and the second reel.
21. In an electric locomotive, the combi- 130

5 nation of a main frame, axles and track wheels upon which the frame is mounted, a motor for driving the locomotive, a rotatable shaft on the locomotive, a reel rotatably mounted on the locomotive and adapted to 10 wind and unwind an electrical conductor cable, a second reel adapted to wind and unwind a haulage cable, a power transmitting connection comprising a manually controllable clutch between the rotatable shaft and the first reel, and a power transmitting connection between the shaft and the second reel.

15 22. In an electric locomotive, the combination of a main frame, axles and track wheels upon which the frame is mounted, a motor for driving the locomotive, a rotatable shaft on the locomotive, a reel rotatably mounted on the locomotive and adapted to 20 wind and unwind an electrical conductor cable, a second reel adapted to wind and unwind a haulage cable, a power transmitting connection comprising a manually controllable clutch and frictionally engaging elements between the rotatable shaft and the first reel, and a power transmitting connection between the shaft and the second reel.

25 23. In an electric locomotive, the combination of a main frame, axles and track wheels upon which the frame is mounted, a motor for driving the locomotive, a rotatable shaft on the locomotive, a reel rotatably mounted on the locomotive and adapted to 30 wind and unwind an electrical conductor cable, a second reel adapted to wind and unwind a haulage cable, a power transmitting connection comprising two yieldably engaging friction elements between the rotatable shaft and the first reel, and a power transmitting connection comprising a manually controllable clutch between the shaft and the second reel.

35 24. The combination of the car, the motor adapted to propel the car, the reel for an electric conductor cable, the reel for a draft cable or haulage cable, a shaft for driving both of said reels, and means for disconnecting each of said reels from said shaft.

40 25. In an electric locomotive, the combination of a main frame, axles and track wheels upon which the frame is mounted, a motor for driving the locomotive, a rotatable shaft on the locomotive, a reel rotatably mounted on the locomotive and adapted to 45 wind and unwind an electrical conductor cable, a second reel adapted to wind and unwind a haulage cable, a power transmitting connection comprising a manually controllable clutch and yieldably engaging friction elements between the rotatable shaft and the first reel, and a power transmitting connection comprising a manually controllable clutch between the shaft and the second reel.

45 26. In an electric locomotive, the combination of a main frame, axles and track wheels upon which the frame is mounted, a motor for driving the locomotive, a rotatable shaft on the locomotive, a reel rotatably mounted on the locomotive and adapted to 50 wind and unwind an electrical conductor cable, a second reel adapted to wind and unwind a haulage cable, and two friction controlled power transmitting mechanisms, one interposed between the shaft and the first reel and the other interposed between the shaft and the second reel.

55 nation of a main frame, axles and track wheels upon which the frame is mounted, a motor for driving the locomotive, a rotatable shaft on the locomotive, a reel rotatably mounted on the locomotive and adapted to 60 wind and unwind an electrical conductor cable, a second reel adapted to wind and unwind a haulage cable, and two friction controlled power transmitting mechanisms, one interposed between the shaft and the first reel and the other interposed between the shaft and the second reel.

65 27. In an electric locomotive, the combination of a frame, axles and track wheels upon which the frame is supported, a motor for driving the locomotive, a reel rotatably mounted upon the locomotive and adapted for winding and unwinding an electric conductor cable, a second reel rotatably mounted on the locomotive in axial alignment with the first reel and adapted for winding and unwinding a haulage cable, a rotatable shaft on the locomotive, and power transmitting connections between the shaft and the two reels.

70 28. In an electric locomotive, the combination of a frame, axles and track wheels upon which the frame is supported, a motor for driving the locomotive, a reel rotatably mounted upon the locomotive and adapted for winding and unwinding an electric conductor cable, a second reel rotatably mounted on the locomotive in axial alignment with the first reel and adapted for winding and unwinding a haulage cable, a rotatable shaft mounted coaxially with the two reels, and power transmitting connections between the shaft and each of the reels.

75 29. In a locomotive, the combination of a motor adapted to propel the locomotive, a conductor cable reel and a haulage cable reel mounted co-axially, a driving shaft for the said reels mounted co-axially with respect to the said reels, a clutch mechanism interposed between the driving shaft and the haulage cable reel, and a clutch mechanism interposed between the driving shaft and the conductor cable reel.

80 30. In a locomotive, the combination of a motor adapted to propel the locomotive, a conductor cable reel and a haulage cable reel mounted co-axially, a driving shaft for said reels, a clutch mechanism interposed between the driving shaft and the haulage cable reel, and a clutch mechanism interposed between the driving shaft and the conductor cable reel.

85 31. In an electric locomotive, the combination of a main frame, axles and track wheels upon which the frame is mounted, a motor for driving the locomotive, a reel mounted upon the locomotive to rotate about a vertical axis, the said reel being adapted to wind and unwind an electric conductor cable, a second reel mounted co-axially with

the first reel and adapted to wind and unwind a haulage cable, a rotatable shaft, and power connections between the shaft and each of the reels.

- 5 32. In an electric locomotive, the combination of a main frame, axles and track wheels upon which the frame is mounted, a motor for driving the locomotive, a reel mounted upon the locomotive to rotate about 10 a vertical axis, the said reel being adapted to wind and unwind an electric conductor cable, a second reel mounted co-axially with the first reel and adapted to wind and unwind a haulage cable, a vertical rotatable 15 shaft mounted co-axially with the said reels, and power transmitting connections between the shaft and each of the reels.

33. In an electric locomotive, the combination of a main frame, axles and track 20 wheels upon which the frame is mounted, a motor capable of being operated independently of the axles and the track wheels, a reel rotatably mounted on the locomotive and adapted for winding and unwinding an 25 electric conductor cable, a second rotatably mounted reel adapted for winding and unwinding a haulage cable, and power connections between the motor and each of the 30 reels.

34. In an electric locomotive, the combination of a main frame, axles and track 35 wheels upon which the frame is mounted, a motor capable of being operated independently of the axles and the track wheels, a reel rotatably mounted on the locomotive and adapted for winding and unwinding an 40 electric conductor cable, a second rotatably mounted reel adapted for winding and unwinding a haulage cable, a power connection from the motor to the first reel, and a power 45 connection comprising a manually controllable clutch between the motor and the second reel.

35. In an electric locomotive, the combination of a main frame, axles and track 50 wheels upon which the frame is mounted, a motor capable of being operated independently of the axles and the track wheels, a reel rotatably mounted on the locomotive and adapted for winding and unwinding an 55 electric conductor cable, a second rotatably mounted reel adapted for winding and unwinding a haulage cable, a power transmitting connection between the motor and the first reel, and a power transmitting connection comprising a manually controllable friction clutch interposed between the motor and the second reel.

36. In an electric locomotive, the combination of a main frame, axles and track 60 wheels upon which the frame is mounted, a motor capable of being operated independently of the axles, and the track wheels, a reel rotatably mounted on the locomotive 65 and adapted for winding and unwinding an

electric conductor cable, a second rotatably mounted reel adapted for winding and unwinding a haulage cable, a yieldable friction controlled power transmitting connection between the motor and the first reel and 70 a power transmitting connection between the motor and the second reel.

37. In an electric locomotive, the combination of a main frame, axles and track 75 wheels upon which the frame is mounted, a motor capable of being operated independently of the axles and the track wheels, a reel rotatably mounted on the locomotive and adapted for winding and unwinding an electric conductor cable, a second rotatably 80 mounted reel adapted for winding and unwinding a haulage cable, a power transmitting connection comprising a manually controllable clutch between the motor and the first reel, and a power transmitting connection between the motor and the second reel.

38. In an electric locomotive, the combination of a main frame, axles and track 85 wheels upon which the frame is mounted, a motor capable of being operated independently of the axles and the track wheels, a reel rotatably mounted on the locomotive and adapted for winding and unwinding an electric conductor cable, a second rotatably 90 mounted reel adapted for winding and unwinding a haulage cable, power transmitting connection comprising a manually controllable clutch and frictionally engaging elements between the motor and the first reel, and a power transmitting connection 95 between the motor and the second reel.

39. In an electric locomotive, the combination of a main frame, axles and track 100 wheels upon which the frame is mounted, a motor capable of being operated independently of the axles and the track wheels, a reel rotatably mounted on the locomotive and adapted for winding and unwinding an electric conductor cable, a second rotatably 105 mounted reel adapted for winding and unwinding a haulage cable, a power transmitting connection comprising two yieldably engaging friction elements between the rotatable motor and the first reel, and a power 110 transmitting connection comprising a manually controllable clutch between the motor and the second reel.

40. In an electric locomotive, the combination of a main frame, axles and track 115 wheels upon which the frame is mounted, a motor capable of being operated independently of the axles and the track wheels, a reel rotatably mounted on the locomotive and adapted for winding and unwinding an electric conductor cable, a second rotatably 120 mounted reel adapted for winding and unwinding a haulage cable, power transmitting devices between the motor and each of the reels, and means for disconnecting each of the 125 reels from the motor.

41. In an electric locomotive, the combination of a main frame, axles and track wheels upon which the frame is mounted, a motor capable of being operated independently of the axles and the track wheels, a reel rotatably mounted on the locomotive and adapted for winding and unwinding an electric conductor cable, a second rotatably mounted reel adapted for winding and unwinding a haulage cable, a power transmitting connection comprising a manually controllable clutch and yieldably engaging friction elements between the motor and the first reel, and a power transmitting connection comprising a manually controllable clutch between the motor and the second reel.
42. In an electric locomotive, the combination of a main frame, axles and track wheels upon which the frame is mounted, a motor capable of being operated independently of the axles and the track wheels, a reel rotatably mounted on the locomotive and adapted for winding and unwinding an electric conductor cable, a second rotatable reel adapted for winding and unwinding a haulage cable, and two friction controlled power transmitting mechanisms, one interposed between the motor and the first reel and the other interposed between the motor and the second reel.
43. In an electric locomotive, the combination of a main frame, axles and track wheels upon which the frame is mounted, an electric motor capable of being operated independently of the axles and track wheels, a reel rotatably mounted on the locomotive and adapted for winding and unwinding an electric conductor cable, a second reel in axial alignment with the first reel and adapted for winding and unwinding a haulage cable, and power connections between the motor and each of the reels.
44. In an electric locomotive, the combination of a main frame, axles and track wheels upon which the frame is mounted, an electric motor capable of being operated independently of the axles and track wheels, a reel mounted on the locomotive for rotation about a vertical axis, the said reel being adapted to wind and unwind an electric conductor cable, a second reel mounted for rotation about a vertical axis coincident with the vertical axis of the first reel, the said second reel being adapted to wind and unwind a haulage cable, and power transmitting connections between the motor and each of the reels.
45. In a haulage locomotive, a motor, means for transmitting motion from the motor to the locomotive, a reel, a haulage cable carried by said reel, a second rotatably mounted reel, and means for transmitting motion from the motor to either or both of said reels.
46. The combination of the car, the motor thereon, a reel for an electric cable, a reel for a draft cable or haulage cable, power transmitting devices between the motor and the car axle, power transmitting devices adapted to drive both of the aforesaid reels, the clutch for disconnecting the axle from its power transmitting devices, the clutch for disconnecting the power transmitting devices from the draft cable reel, and the clutch for disconnecting the power transmitting devices from the conductor cable reel.
47. The combination in a locomotive, of a motor, a reel for winding and unwinding an electric conductor cable, a second reel for winding and unwinding a haulage cable, and power connections whereby the locomotive motor is adapted to transmit power to rotate the conductor cable reel, the haulage cable reel and the car axle.
48. In a locomotive, the combination of a car, a motor thereon, a reel adapted for winding and unwinding an electric conductor cable, a second reel for a draft or haulage cable, power transmitting devices between the motor and one of the axles, and other additional power transmitting devices connecting the power transmitting devices aforesaid with both reels and adapted to transmit power from the axle to both reels when the motor is deenergized.
49. In an electric locomotive, the combination of a main frame, axles and track wheels upon which the frame is supported, a motor, a manually controllable clutch between the motor and one of the axles, a reel rotatably mounted on the locomotive and adapted to wind and unwind an electric conductor cable, a second rotatable reel adapted for winding and unwinding a haulage cable, a power transmitting connection comprising a clutch between the motor and the first reel, and a power transmitting mechanism comprising a clutch between the motor and the second reel.
50. In an electric locomotive, the combination of a main frame, axles and track wheels upon which the frame is supported, a motor, a manually controllable clutch between the motor and one of the axles, a reel rotatably mounted on the locomotive and adapted to wind and unwind an electric conductor cable, a second rotatable reel adapted for winding and unwinding a haulage cable, a power transmitting mechanism between the motor and the first reel, and a yieldable frictionally controlled power transmitting mechanism between the motor and the second reel.
51. In an electric locomotive, the combination of a main frame, axles and track wheels upon which the frame is supported, a motor, a manually controllable clutch between the motor and one of the axles, a reel

5 rotatably mounted on the locomotive and adapted to wind and unwind an electric conductor cable, a second rotatable reel adapted for winding and unwinding a haulage cable, a yieldable frictionally controlled power transmitting mechanism between the motor and the first reel, and a power transmitting mechanism between the motor and the second reel.

- 10 52. In an electric locomotive, the combination of a main frame, axles and track wheels, upon which the frame is supported, a motor, a manually controllable clutch between the motor and one of the axles, a reel 15 rotatably mounted on the locomotive and adapted to wind and unwind an electric conductor cable, a second rotatable reel adapted for winding and unwinding a haulage cable, and two yieldable frictionally 20 controlled power transmitting mechanisms, one interposed between the motor and the first reel and the other interposed between the motor and the second reel.

25 53. The combination of a car, a motor adapted to propel the car, a reel on the car adapted for winding an electric cable in either direction of winding, drive shafting for the reel adapted to be driven in one direction by the movement of the locomotive 30 with one end in advance and adapted to be driven in the other direction of rotation by the movement of the locomotive with the other end in advance, and a clutch adjustable either to transmit power to drive the 35 reel from the drive shafting, only when the shafting is rotating in one direction, or, on the other hand, to transmit power from the drive shafting to rotate the reel in the other direction only when the said drive 40 shafting is rotating in the other direction.

45 54. The combination of the car, a motor adapted to propel the car, a reel mounted on the car adapted to wind an electric conductor cable in either direction of winding, and power transmitting gearing adapted to 50 drive the reel and comprising a three-part clutch of which the second part is adapted to be made rigid with the first part so as to form a clutch adapted to drive the reel in one direction only and adapted to be made at other times rigid with the third part so as to provide a clutch for rotating the reel in the opposite direction only.

55 55. The combination of a car, a motor adapted to propel the car, a rotatable shaft, a reel driven by the shaft and adapted for winding an electric conductor cable in either direction of winding, the direction in which the cable is wound upon the reel corresponding to the end of the locomotive which is pointed toward the fixed point of cable attachment, and clutch mechanism for the shaft having two pairs of clutch members, those of one pair being adapted to rotate the 60 shaft in one direction only and those of the

other pair being adapted to rotate the shaft in the opposite direction only.

56. The combination in a locomotive, of an electric motor adapted to propel the locomotive, a cable reel adapted for winding an 70 electric conductor cable in either direction, the direction of winding of the cable corresponding to the end of the locomotive which is pointed toward the fixed point of cable attachment, power mechanism for operating 75 the reel reversible in direction depending upon the direction of movement of the locomotive, and a reversible single-direction drive positive clutch operatively interposed between the power mechanism and the reel. 80

57. The combination in a locomotive, of an electric motor adapted to propel the locomotive, a cable reel adapted for winding an electric conductor cable in either direction, the direction of winding of the cable cor- 85 responding to the end of the locomotive which is pointed toward the fixed point of cable attachment, power mechanism for operating the reel reversible in direction depending upon the direction of movement of 90 the locomotive, a reversible single-direction drive positive clutch operatively interposed between the power mechanism and the reel, and a reversible device connected with the reel for preventing rotation of the reel in 95 one direction at some times or in the other direction at other times, as may be desired.

58. In an electric locomotive, the combination of a main frame, axles and track wheels upon which the frame is mounted, a 100 motor connected with one of the axles to propel the locomotive in either direction, a rotatable reel adapted for winding or unwinding an electric conductor cable, a power shaft for the reel connected to be rotated in 105 one direction or the other in accordance with the direction of movement of the locomotive, and power transmitting mechanism between the shaft and the reel comprising a friction clutch and a second clutch adjustable either 110 to transmit power from the shaft to the reel only when the shaft is rotating in one direction or to transmit power from the shaft to the reel only when the shaft is rotating in the other direction. 115

59. In an electric locomotive, the combination of a main frame, axles and track wheels upon which the frame is mounted, a motor connected with one of the axles to propel the locomotive in either direction, a rotatable reel adapted for winding or unwinding an electric conductor cable, a power shaft for the reel connected to be rotated in one direction or the other in accordance with the direction of movement of the locomotive, power transmitting mechanism between the shaft and the reel comprising a friction clutch and a second clutch adjustable either to transmit power from the shaft to the reel only when the shaft is rotating 120 125 130 135 140 145 150 155 160 165 170 175 180

in one direction or to transmit power from the shaft to the reel only when the shaft is rotating in the other direction, a second reel adapted for winding and unwinding a haulage cable, and a power connection between the said shaft and the second reel.

60. In an electric locomotive, the combination of a main frame, axles and track wheels upon which the frame is mounted, a motor connected with one of the axles to propel the locomotive in either direction, a rotatable reel adapted for winding or unwinding an electric conductor cable, a power shaft for the reel connected to be rotated in one direction or the other in accordance with the direction of movement of the locomotive, power transmitting mechanism between the shaft and the reel comprising a friction clutch and a second clutch adjustable either to transmit power from the shaft to the reel only when the shaft is rotating in one direction or to transmit power from the shaft to the reel only when the shaft is rotating in the other direction, a second reel adapted for winding and unwinding a haulage cable, and a power connection comprising a manually controllable clutch between the shaft and the second reel.

61. In an electric locomotive, the combination of a main frame, axles and track wheels upon which the frame is yieldably mounted, a motor operatively connected with one of the axles and partly supported thereby, a longitudinal power shaft operatively connected with the motor and mounted in bearings rigidly secured to the motor, a cable winding mechanism rigidly connected with the locomotive frame, a longitudinal drive shaft for the cable winding mechanism mounted in bearings rigid therewith, and a flexible power connection between the said power shaft and the said drive shaft of the winding mechanism.

62. In an electric locomotive, the combination of a main frame, axles and track wheels upon which the frame is yieldably supported, an electric motor operatively connected with one of the axles and supported in part thereby, a longitudinal power shaft operatively connected with the motor and mounted in bearings rigidly secured thereto, a cable winding mechanism rigidly mounted on the locomotive frame, a longitudinal drive shaft for the cable winding mechanism mounted out of alignment with the said power shaft in bearings rigidly secured to the winding mechanism, and a power connection comprising a chain between the said power shaft and the said drive shaft.

63. In an electric locomotive, the combination of a main frame, axles and track wheels upon which the frame is mounted, a motor operable independently of the axles and track wheels, two rotatable shafts in alignment, a manually controllable clutch for con-

nnecting the shafts, a power connection between the motor and one of the shafts, a rotatable reel operably connected with one of the shafts, the said reel being adapted to wind and unwind an electric conductor cable, and a second reel operably connected with the other of the shafts and adapted to wind and unwind a haulage cable.

64. In an electric locomotive, the combination of a main frame, axles and track wheels upon which the frame is mounted, a motor operable independently of the axles and the track wheels, two rotatable vertical shafts mounted in alignment with each other, a manually controllable clutch for connecting the shafts, a power connection between the motor and one of the shafts, a reel mounted co-axially with the upper of the shafts, a friction clutch interposed between the said shaft and the reel, a second reel mounted co-axially with the lower of the shafts and adapted to wind and unwind a haulage cable, and a manually controllable clutch between the lower of the shafts and the said second reel.

65. In an electric locomotive, the combination of a main frame, axles and track wheels upon which the frame is mounted, a motor for driving the locomotive, a rotatable shaft on the locomotive, power connections between one of the axles and the said shaft, a rotatable reel adapted to wind and unwind an electric conductor cable, a power transmitting connection between the said shaft and the reel comprising a manually controllable positive clutch and a friction clutch, and a brake automatically operative to retard the rotation of the reel in one direction and to permit its free rotation in the other direction.

66. In an electric locomotive, the combination of a main frame, axles and track wheels upon which the frame is supported, a motor operable independently of the axles and the track wheels, a reel mounted for rotation about a vertical axis, the said reel being adapted to wind and unwind a cable, a rotatable friction clutch element, a power connection between the motor and the said rotatable friction clutch element, a second friction clutch element connected with the reel, and means controllable by the operator for moving the reel vertically to bring the friction clutch element secured to it into engagement with the friction clutch element which is connected with the motor.

67. In an electric locomotive, the combination of a main frame, axles and track wheels upon which the frame is mounted, a motor operable independently of the axles and track wheels, a rotatably mounted reel adapted for winding and unwinding a haulage cable, two friction clutch elements, one connected with the reel and one connected with the motor to be rotated thereby, and

means within the control of the operator for moving the reel axially to cause the operative engagement of the two clutch elements.

68. In an electric locomotive, the combination of a main frame, axles and track wheels upon which the frame is supported, a motor operable independent of the axles and the track wheels, a reel mounted for rotation about a vertical axis, the said reel being adapted to wind and unwind a cable, a rotatable friction clutch element above the reel, a power connection between the motor and the said rotatable friction clutch element, a second friction clutch element connected with the reel, and means controllable by the operator for turning the said ring and thereby raising or lowering the reel to bring the friction clutch element secured to it into or out of engagement with the friction clutch element which is connected with the motor.

69. In an electric locomotive, the combination of a main frame, axles and track wheels upon which the frame is supported, a motor operable independent of the axles and the track wheels, a reel mounted for rotation about a vertical axis, the said reel being adapted to wind and unwind a cable, a series of inclined teeth on the bottom of the reel, a rotatable ring having similarly in-

clined teeth which engage the teeth on the reel to support it, a rotatable friction clutch element above the reel, a power connection between the motor and the said rotatable friction clutch element, a second friction clutch element connected with the reel, and means controllable by the operator for turning the said ring and thereby raising or lowering the reel to bring the friction clutch element secured to it into or out of engagement with the friction clutch element which is connected with the motor.

70. In an electric locomotive, the combination of a main frame, axles and track wheels, upon which the frame is mounted, a motor for propelling the locomotive, a winding mechanism having a reel for an electric conductor cable, and a reel for a haulage cable, a frame upon which the entire winding mechanism is supported, the said frame being structurally independent of the locomotive frame, and cross bars secured at their ends in the locomotive frame and supporting the winding mechanism frame intermediate their ends.

In testimony whereof I affix my signature, in presence of two witnesses.

FRANK L. SESSIONS.
